UNITED STATES PATENT OFFICE

109,696

DESIGN FOR A TEXTILE FABRIC

Jacques Cipoth, Mamaroneck, N. Y.

Application April 2, 1938, Serial No. 76,231

Term of patent 3½ years

To all whom it may concern:

Be it known that I, Jacques Cipoth, a citizen of the United States and a resident of Mamaroneck, in the county of Westchester and State of New York, whose post office address is 514 Prospect Avenue, Mamaroneck, New York, have invented a new, original, and ornamental Design for a Textile fabric, of which the following is a specification, reference being had to the accompanying drawing constituting a part thereof:

The figure is a plan view of a piece of the textile fabric showing my new design.

I claim:

The ornamental design for a textile fabric substantially as shown.

JACQUES CIPOTH.
